CATALYTIC CONVERSION OF HYDRO-CARBON OILS

Charles W. Tyson, Summit, N. J., assignor to
Standard Oil Development Company, a corpora-
tion of Delaware

Application May 24, 1941, Serial No. 394,963

18 Claims. (Cl. 196—50)

This invention relates to the catalytic conversion of hydrocarbon oils and pertains more particularly to a process for treating crude petroleum oils to form lower boiling motor fuel products.

One of the important objects of the present invention is to provide a process for cracking oils in the presence of a catalyst in finely-divided form which is capable of converting a greater proportion of the original oil into motor fuel products than is possible according to present processes.

It has heretofore been proposed to form motor fuel by cracking petroleum oil in the presence of a catalyst. According to one general method of procedure, the catalyst in finely-divided state is mixed with the oil vapors to be cracked and the resulting mixture passed through a cracking zone. The present invention deals particularly with a process of this type.

When operating in this manner, the catalyst more or less rapidly becomes contaminated with carbonaceous deposits which impair the activity of the catalyst for bringing about the desired cracking. It is necessary, therefore, to regenerate the catalyst at frequent intervals to restore its activity. The regeneration may be accomplished by controlled oxidation, in which the catalyst is treated with an oxidizing gas at a temperature which will burn off the carbonaceous deposits without permanently injuring the activity of the catalyst.

Since the time required for effecting the regeneration is non-productive, it has been the practice in the past to utilize as an oil for the cracking process a relatively clean condensate stock so that the amount of coke formed during cracking can be held to a minimum. This method of operating requires that the original crude petroleum be initially subjected to a distilling operation so as to distill or vaporize the charging stock employed for catalytic cracking purposes. It also necessitated the rejection of a residual fraction of the crude oil which could not be vaporized without decomposition.

The process forming the present invention makes it possible to utilize the residual unvaporizable portion of the crude oil which has been previously rejected as well as the clean condensate portions previously employed for catalytic cracking purposes. The invention will be better understood from the more detailed description hereinafter in which reference will be made to the accompanying drawing which is a diagrammatic

illustration of an apparatus suitable for carrying the invention into effect.

Referring to the drawing, the reference character 10 designates a charge line through which the oil to be processed is introduced into the equipment. This oil is preferably a residual stock, such as a crude oil, topped crude, reduced crude, or the like. For example, it may be the total crude fraction or a crude petroleum fraction from which the gasoline has been removed or a fraction from which the gasoline and a portion or all of the kerosene or gas oil has been removed. The oil charged through line 10 is forced by means of pump 11 through a suitable heat exchanger 12 in which the oil may be preheated in any desired manner. The amount of preheating should be controlled to maintain a major portion of the oil in liquid phase. The heat exchanger 12 may be located, if desired, so as to exchange heat between the incoming stream and hot oil products or catalyst.

After passing through the heat exchanger 12, there is introduced through line 13 into the stream of oil to be processed a finely-divided catalytic material suitable for effecting the cracking of hydrocarbon oils. This catalytic material should consist of an absorptive material having a high absorptive capacity for heavy liquid oil and may comprise, for example, either natural or activated clays or synthetic absorptive products of the same or different chemical composition. For example, synthetic gel catalysts consisting of silica-alumina, silica-magnesia, boron oxide-alumina and silica-zirconia have been found to be effective for this purpose. In order to introduce the catalyst powder into the oil stream, it is necessary to impose a pressure on the powder sufficient to overcome the pressure existing in the stream of oil. According to the drawing, the necessary pressure is developed by constructing line 13 in the form of a vertical column or standpipe having a height sufficient to develop a static pressure at the bottom thereof adequate to overcome the pressure of the oil. In order to prevent the catalyst from bridging across the column or standpipe 13, a fluidizing medium such as an inert gas may be introduced at one or more spaced points through lines 14, 15, 16 and 17.

The bottom portion of the standpipe 13 may be provided with a valve 18 for regulating the amount of powdered material introduced into the oil vapors. A suitable inert gas such as steam may be also introduced into the conduit 13 below valve 18 through line 19 to maintain the powder

in fluidized form and to prevent oil vapors from contacting the operating valve 18.

The amount of powdered catalyst introduced into the oil stream through line 13 may range from 100% to 450% of the unvaporizable portion of the oil stream. Expressed in another way, the amount of such powder so introduced should be sufficient to absorb all of the unvaporizable residue without becoming tacky or sticky. It is understood that the term "unvaporizable residue" means that portion of the oil which does not readily vaporize at operating pressure without substantial decomposition.

As a typical example, where the amount of unvaporizable oil amounts to about 10% of the crude, the amount of powdered material introduced should be from 100% to 450% by weight of the unvaporizable portion. Where undistilled crude is employed in the process, this amount will correspond in such case from 10% to 45% by weight of the fresh feed introduced through line 10.

The amount of powder to be introduced in each particular case should be controlled to completely absorb or adsorb all the unvaporizable constituents without becoming tacky or sticky and will depend on the character of the feed, the absorptive properties of the catalyst, and other factors. In ordinary cases, when employing either absorptive clays or synthetic gels, the amount will be somewhere within the above limits.

The mixture of catalyst and oil formed in line 10 passes to a separating chamber 20 in which gases and vapors separate from a liquid residue containing the catalyst. The gases and vapors will consist of the fluidizing gas mixed with the powder and hydrocarbon vapors formed during preheating the oil in heat exchanger 12. According to one method of operating, the amount of heat imparted to the oil during its passage through the heat exchanger 12 may be sufficient to vaporize a portion of the oil, but it will be necessary to retain a sufficient amount of oil in unvaporized form to form a liquid slurry in the separator 20 which may be readily pumped by means of a liquid pump and which will form a sufficient amount of vapors during the subsequent treatment to serve as a carrier for the powder contained in the slurry and thus prevent the powder from separating out in the vaporizing coil.

Vapors and gases separated in the separator 20 pass overhead through line 21 and are treated as hereinafter described. The liquid slurry separated in the separator 20 is withdrawn through line 22 and is forced by means of a pump 23 to a heating and vaporizing coil 24 in which the slurry is heated to a temperature sufficient to vaporize all constituents vaporizable without substantial decomposition. The pump 23 may be automatically controlled by a liquid level controller (not numbered) provided in the separatory chamber 20 whereby the liquid level in the chamber may be maintained between desired limits. As previously mentioned, the amount of powder present should be sufficient to absorb the unvaporizable portion of the original charge without becoming sticky or tacky. Under proper conditions the products leaving the coil 24 will consist of oil vapors and dry powder.

The temperature of the oil obtained during passage through the vaporizing coil 24 may be of the order of from 700° F. to 1000° F. The sus-

pension of vapors and powder may be passed from the heating coil 24 through transfer line 25 into the bottom section of a vertical reactor 26.

The velocity of the vapors passing through the vertical reactor 26 should be controlled so as to permit a partial settling of the powdered material introduced therein. In other words, the velocity of the gases passing through the vertical column should be insufficient to cause the powdered material to travel through the reactor at substantially the same rate as the oil vapors. As a result the density of the mixture within the vertical column 26 will be materially higher than the density of the stream passing thereto and the time required for passage of powder through the reactor will be materially longer than the time required for passage of oil vapors. Under normal conditions the average density of the gas-powder mixture within the vertical tower should be at least twice the density of the stream passing thereto.

The time of residence of the powder in the vertical chamber 26 may be controlled by regulating the velocity of the vapors, the size of the particles, and by other factors so as to convert the residual material absorbed within the powder into oil vapors suitable for further cracking treatment. If desired, additional heat may be supplied to the mixture of oil vapors and powder passing through the reactor 26.

In lieu of passing the total products from the vaporizing coil 24 to chamber 26, the vapors may be first segregated from the powder and only the powder passed to the coking chamber 26. To this end a part or all of the products from the transfer line 25 may be passed through line 27 to a cyclone separator 28 or other equivalent separators for separating solids from gases. Vapors separated in cyclone separator 28 are removed overhead through line 29 and may be combined with the gas stream in line 21.

The powder separated in cyclone separator 28 containing the unvaporized residue absorbed therein discharges through conduit 30 into a hopper 31 from whence it is fed through pipe 32 into transfer line 25 leading to the coking vessel 26. When operating in this manner, a heating, stripping and carrier gas from an external source may be used for carrying the powder through the coking vessel. Such gas may be introduced through line 33 and may comprise steam, carbon dioxide, nitrogen, spent combustion gases, or the like. If desired, a small amount of oxygen may be admitted with the carrier gas which may be used to burn a portion of the residual oil contained in the powder to supply additional heat.

According to the embodiment hereinbefore described, the powder for absorbing the unvaporizable residue is added to the oil and the resulting mixture passed through the vaporizing zone. In some cases it may be desirable to add the powder to the oil stream to absorb the unvaporizable residue after vaporization of the bulk of the oil has been accomplished. When operating in this manner, a part or all of the powder from standpipe 13 may be passed to the outlet of the vaporizing coil 24. For simplicity I have shown a branch line 34 leading from the standpipe 13 to the line 27. In practical operation it will be necessary to provide either a gravity flow or some transfer means such as gas for carrying the powder to the line 27. In some cases the heat exchanger 12 may be in the form of a vaporizing coil. In such case the powder may be injected into the outlet of the heat exchanger and the resulting

mixture passed through line 35 directly to the cyclone separator 28.

As a further alternative the absorbent powder may be mixed with the residue after separation of a part or all of the vapors. For example, the powder may be passed from standpipe 13 through conduits 34 and 36 to the draw-off line 22 leading from the separator 20.

The suspension of vapors and the finely-divided catalyst containing the coke resulting from the 10 distilling and vaporizing treatment within the vertical tower 26 is transferred through line 37 and is admixed with gases and vapors in line 21 which leads to a main cracking chamber 38. However, before passing into the cracking chamber, an additional supply of fresh catalyst is mixed with the oil vapors and gases. This additional catalyst may be supplied from a standpipe 39 connected with vapor line 21. The catalyst in standpipe 39 may be maintained in suitable 15 fluidized condition by introducing a suitable fluidizing gas through spaced inlet lines 40, 41 and 42. The amount of fresh catalytic material introduced through standpipe 39 may vary from 2 to 10 parts of catalyst per part of oil by weight. This catalyst is preferably of the same composition as the powder introduced into the fresh oil through line 13 since the two materials become intermingled.

The material introduced into the oil vapors in line 21 is preferably somewhat coarser than the material added to the fresh oil and may be of different chemical composition. In the latter case the material combined with the original oil will contain fines formed by attrition of the coarser catalyst combined with the oil vapors.

The cracking chamber 38 is preferably in the form of a vertical tower with vapors passing upwardly against the force of gravity. The velocity of the oil vapors passing through the cracking chamber 38 is also preferably controlled so that the average time of passage of the catalyst powder through the cracking chamber is materially greater than the time required for the passage of the oil vapors.

The suspension of cracked products and catalyst after passing through the cracking chamber 38 passes through line 43 to a primary cyclone separator 44 wherein the bulk of the powdered catalyst separates from the cracked vapors. The catalyst so separated discharges through line 45 to a catalyst hopper 46.

Vapors from the primary separator pass through line 47 to a secondary cyclone separator 48 wherein further separation of powder from vapors is accomplished. Powder from the second cyclone separator 48 discharges through line 49 into the catalyst hopper 46. Vapors from the secondary separator 48 may pass through line 50 to a third cyclone separator 51 wherein final purification and separation is carried out. Finely-divided catalyst from the third cyclone 51 discharges through line 52 to catalyst hopper 46.

The cracked vapors after passing through the cyclone separators 44, 48 and 51 pass through line 53 to a fractionating tower 54 in which the products are fractionated to condense insufficiently cracked constituents as reflux condensate. Vapors remaining uncondensed in the fractionating tower 54 and consisting primarily of normally gaseous hydrocarbons and motor fuel vapors pass overhead through line 55 to a condenser 56 in which the motor fuel vapors are condensed. Products from the condenser 56 pass to a product receiver 57 in which the liquid distillate separates from uncondensed gases. Gases separated in the

receiver 56 are withdrawn therefrom through line 51a and may be passed to a suitable gas recovery system (not shown) for removing entrained motor fuel products contained therein. The liquid motor fuel distillate separated in the receiver 57 may be removed therefrom through line 58 and may be subjected to any further finishing treatment desired for the production of the final market product.

Returning again to the catalyst hopper 46, the catalyst collected therein discharges into a standpipe 59 into which a fluidizing medium may be introduced through one or more branch lines 60, 61 and 62. The height of the standpipe 59 should be sufficient to develop a pressure at the bottom thereof adequate to feed the catalyst into a stream of air or other regenerating gas introduced into the system through line 63. The standpipe 59 is preferably provided with a suitable valve 64 for controlling the amount of catalyst introduced into the regenerating gas. The mixture of regenerating gas and catalyst formed in line 63 is passed into a regenerating chamber 65 which is also preferably in the form of a vertical tower through which the suspension passes upwardly against the force of gravity. The velocity of the gas passing through the regenerator 65 is controlled to maintain the powder within the regenerating chamber for a period sufficient to remove the carbonaceous deposits formed thereon during the cracking operation. After passing through the regenerating chamber 65, the suspension of regenerating gas and regenerated catalyst passes through line 66 to a primary cyclone separator 67 which serves to remove the bulk of the coarser particles of regenerated catalyst. The catalyst separated from the regenerating gas in the primary cyclone separator 67 discharges into a catalyst hopper 68 from which it passes into the standpipe 39 leading to the oil vapor line 21.

In order to control the temperature within the regenerating chamber 65, it may also be desirable to cool a portion of the regenerated catalyst and recirculate it to the regenerating chamber to absorb heat therein. To this end a portion of the regenerated catalyst in the hopper 68 may be passed through standpipe 69 and discharged through valve 70 into a stream of air or other carrier gas introduced through line 71. Standpipe 69 may be aerated by injecting a fluidizing gas by means of connections 40a, 41a and 42a. The resulting mixture then passes through line 72 to a cooler 73 in which the temperature of the suspension is cooled prior to being returned to the regenerating chamber 65.

The gases from the primary cyclone separator 67 containing a portion of the finer catalyst particles pass through line 74 to a secondary cyclone separator 75 in which further separation of entrained powder from the regenerating gas is accomplished.

Gases from the second cyclone separator 75 may be passed through line 76 to a third cyclone separator 77 for further purification. Gases from the third cyclone separator 77 may be passed through line 78 to an electrical precipitator 79 for final purification. Gases from the electrical precipitator 79 may be vented from the system through line 80. These gases may be passed, if desired, to suitable heat recovery system for recovering energy in the form of heat or pressure before being rejected to the atmosphere.

The finer portions of the catalyst separated in the secondary and tertiary cyclones and elec-

trical precipitator are collected in a catalyst hopper 81. A portion of this fine powder discharges into the standpipe 13 and is remixed with the fresh oil introduced into the process. Any excess of the fine powder collected in the hopper 81 may be discharged through standpipe 82 into the standpipe 39 leading to the oil vapor stream in line 21. For example, line 82 may be provided with an automatic valve 82' controlled by the level of catalytic material in the hopper 81 so as to maintain the catalyst level within the hopper at the desired point.

One of the features of the present invention is to utilize the finer portion of the catalyst powder for contacting with the fresh feed. By utilizing this portion of the catalyst, any inorganic material present in the crude becomes deposited on the finer particles of the catalyst, and since this material is first to be carried out of the system and lost, no permanent harm is done. For example, the amount of fine powder employed for admixing with the initial feed may amount to from 5 to 10% of the total amount of the material employed in the process. Consequently, any inorganic material present in the crude will be collected or accumulated on this relatively small proportion of the total catalyst used. If, for example, the amount of inorganic material is of the order of 50 pounds per thousand barrels of reduced crude, which is a typical example, and the rate of catalyst lost per day is of the order of one pound per barrel of oil treated, the amount of catalyst contamination with inorganic deposits will not exceed more than about 4% by weight on the catalyst. This contamination takes place only on the finest 5-10% of the particles in the system which are the first to be lost. Therefore, the main bulk of the catalyst remains uncontaminated. As a result this contamination will not materially affect the activity of the catalyst for bringing about the desired reaction.

Another important advantage of the present invention is that the coke formed during the vaporization of the heavy residues does not collect on the walls of the heating coil and reaction chamber but is absorbed within a relatively small amount of the total catalyst employed in the process.

A further important feature of the invention is the fact that all of the heating is carried out in the presence of catalytic material so that the amount of thermal cracking is reduced to a minimum.

Having described the preferred embodiment of the invention, it will be understood that it embraces such other variations and modifications as come within the spirit and scope thereof.

What is desired to be protected by Letters Patent is:

1. A process for the conversion of residual oils containing constituents unvaporizable without substantial decomposition under normal pressure conditions which comprises adding to said oil an absorptive powder in an amount sufficient to completely absorb said unvaporizable constituents and form discrete particles of non-adhesive powder, passing the resulting mixture through a heating zone, heating said mixture during passage through said zone to a temperature sufficient to convert said oil into vapors and coke, thereafter passing the resulting mixture of vapors and powder containing said coke through a cracking zone, contacting said mixture within said cracking zone with a cracking catalyst separate and independent from said first-named absorptive con-

tact material to crack said vapors into motor fuel constituents and segregating the motor fuel from the cracked products.

2. A process for the conversion of residual oils containing constituents unvaporizable without substantial decomposition which comprises adding to said residual oil an absorptive powder in an amount sufficient to completely absorb said unvaporizable constituents and form discrete particles of non-adhesive powder, passing the resulting mixture through a heating zone, heating said mixture during passage therethrough to a temperature sufficient to convert said oil into vapors and coke, thereafter passing the mixture of vapors and powder containing said coke from said heating zone to a cracking zone, admixing with the stream of products passing through said cracking zone fresh cracking catalyst in powder form, maintaining said mixture within said cracking zone for a period sufficient to obtain substantial cracking of said vapors, thereafter separating the powder from said cracked products and fractionating the cracked products to separate a motor fuel therefrom.

3. In the process defined in claim 2, the further improvement which comprises subjecting the powder separated from said cracked products to a regenerative treatment to remove carbonaceous and coke deposits formed thereon during the heating, coking and cracking treatments, thereafter segregating the regenerated powder into a relatively coarse fraction and a relatively finer fraction, passing said coarser fraction to said cracking zone and mixing said finer fraction with said first-named residual oil.

4. A process for the conversion of residual oils containing constituents unvaporizable without substantial decomposition under normal pressure conditions which comprises adding to said oil an absorptive powder in an amount sufficient to completely absorb said unvaporizable constituents to form discrete particles of non-adhesive powder, passing the mixture of powder and oil upwardly through an elongated heating zone maintained at a temperature sufficient to convert said oil into vapors and coke, regulating the velocity of the oil passing through said heating zone to maintain said powder therein for a period sufficient to completely convert said unvaporizable constituents into vapors and coke, thereafter passing the resulting mixture of vapors and powder containing said coke through a cracking zone, contacting said mixture within said cracking zone with an additional cracking catalyst in powder form, maintaining said vapors within said cracking zone for a period sufficient to produce substantial cracking thereof, thereafter separating the powder from said cracked products and fractionating the cracked products to segregate a motor fuel fraction therefrom.

5. A process for the conversion of residual oils containing vaporizable constituents and constituents unvaporizable without substantial decomposition under normal pressure conditions which comprises adding to said oil an absorptive powder in an amount sufficient to completely absorb said unvaporizable constituents, passing the resulting mixture through a vaporizing zone maintained at a temperature sufficient to vaporize said vaporizable constituents, thereafter passing the powder containing the unvaporizable constituents absorbed thereon through a heating zone maintained at a temperature sufficient to decompose said unvaporizable constituents into vapors and coke, thereafter passing said mixture of va-

5
pors and powder containing said coke through a cracking zone maintained under conditions to crack said vapors into motor fuel constituents, contacting said mixture within said cracking zone with additional cracking catalyst in powder form, separating the powder from the cracked products and fractionating the cracked products to separate a motor fuel fraction therefrom.

6. If the process defined in claim 5, the further improvement which comprises combining the vapors formed in said vaporizing zone with the vapors and powder formed in said heating zone prior to passing the latter to said cracking zone.

7. In the process defined by claim 5, the further improvement which comprises separating products removed from said vaporizing zone into vapors and powder and passing said powder to said heating zone.

8. In the process defined in claim 5, the further improvement which comprises separating the products from said vaporizing zone into vapors and solids, suspending said solids in an extraneous gas and passing the resulting mixture of powder and gas through said heating zone.

9. In the process defined in claim 5, the further improvement which comprises separating the products from said vaporizing zone into vapors and powder, mixing said powder so separated with an oxidizing gas, passing the resulting mixture of oxidizing gas and powder through said heating zone and controlling the oxygen concentration of said oxidizing gas to partially burn unvaporizable constituents absorbed on said powder to supply additional heat to said heating zone.

10. A process for the conversion of residual oils containing vaporizable constituents and constituents unvaporizable without substantial decomposition under normal pressure conditions which comprises adding to said oil an absorptive powder in an amount sufficient to completely absorb said unvaporizable constituents, passing the resulting mixture of powder and oil through a vaporizing zone, controlling the temperature in said vaporizing zone to vaporize said vaporizable constituents, thereafter passing the products from said vaporizing zone through an additional heating zone, maintaining said heating zone under temperature conditions sufficient to decompose unvaporizable constituents absorbed on said powder into vapors and coke, passing the products from said last-named heating zone through a cracking zone, contacting the products in said last-named cracking zone with an additional cracking catalyst in powder form but composed of coarser particles than said first-named absorptive powder, maintaining the oil vapors within said cracking zone for a period sufficient to produce a substantial cracking into motor fuel constituents, thereafter segregating the powder from the cracked products, fractionating the cracked products to separate a motor fuel fraction, regenerating the powder so separated to remove combustible deposits formed thereon during the heating and cracking treatments, segregating the regenerated powder into a relatively coarse fraction and a relatively fine fraction, mixing said fine fraction with said first-named oil to be treated and returning said coarser fraction to said cracking zone.

11. A process for the conversion of residual oil containing vaporizable constituents and constituents unvaporizable under normal pressure conditions which comprises mixing with said oil an absorptive powder in an amount sufficient to completely absorb the unvaporizable constituents

of said oil, passing the resulting mixture of oil and powder through a vaporizing zone, maintaining said mixture within said zone for a period sufficient to vaporize said vaporizable constituents and form a stream of vapors and relatively dry powder, separating the powder from the oil vapor, passing the resulting powder containing the unvaporizable constituents absorbed thereon through a coking zone, maintaining said coking zone at a temperature sufficient to convert said unvaporizable constituents absorbed in said powder into vapors and coke, combining said last-named vapors with vapors liberated during said vaporizing treatment, passing the resulting vapors through a cracking zone, contacting said vapors with additional cracking catalyst in powder form within said last-named cracking zone, separating the powder from said cracked products, fractionating the cracked products to separate a motor fuel fraction therefrom, subjecting said powder to regenerative treatment to remove combustible deposits formed thereon during said coking and cracking treatment, combining a portion of said regenerated catalyst with said fresh residual oil and passing the remainder thereof to said cracking zone.

12. In the process defined by claim 11, the further improvement which comprises passing said powder upwardly through said coking zone and controlling the velocity of the stream passing through said coking zone to retain said powder therein for a period sufficient to convert said unvaporizable constituents into vapors and a coke residue.

13. A process for the conversion of residual oils containing vaporizable constituents and constituents unvaporizable without substantial decomposition which comprises heating said oil to vaporize a portion thereof, thereafter adding a finely-divided absorbent powder to said heated oil in an amount sufficient to completely absorb the unvaporizable constituents thereof and form a suspension of vapors and powder containing the unvaporized oil, separating the last-named vapors from the powder, passing the powder so separated through a coking zone, maintaining said coking zone at a temperature sufficient to convert said unvaporized oil absorbed in said powder into vapors and coke, passing the vapors and powder containing said coke through a cracking zone independent of said coking zone, contacting said mixture within said cracking zone with an active cracking catalyst, maintaining said cracking zone at a temperature sufficient to convert a substantial portion of said vapors into motor fuel constituents and thereafter separating the motor fuel fraction from the cracked products.

14. In the process defined by claim 13, the further improvement which comprises combining the vapors separated from said powder prior to said coking treatment with the vapors and powder passing to said cracking zone.

15. A process for the conversion of residual oils containing constituents unvaporizable without substantial decomposition which comprises mixing said oil with a finely-divided absorbent powder, adding sufficient powder to said oil to completely absorb all unvaporizable constituents contained therein, heating said oil while in contact with said powder to convert said oil into vapors and a solid residue, passing the resulting vapors and said powder containing the solid residue through a cracking zone, contacting said mixture while in said cracking zone with an active cracking catalyst in finely-divided form, maintaining

said oil vapors within said cracking zone for a period sufficient to convert a substantial portion thereof into motor fuel, thereafter separating the cracked products from the catalyst and powder, and fractionating the cracked products to segregate a motor fuel fraction therefrom.

16. In the process defined by claim 15, the further improvement which comprises regenerating the finely-divided absorbent powder and catalyst separated from the cracked products and remixing the regenerated material with the oil undergoing treatment.

17. In the process defined by claim 11, the further improvement which comprises contacting said powder within the coking zone with an oxidizing gas to maintain said temperature.

18. In a process for cracking residual oils containing inorganic impurities in the presence of a finely divided catalyst having different particle sizes wherein the catalyst is continuously circulated through a cracking zone in which it is con-

tacted with oil to be cracked and through a regenerating zone in which it is contacted with a regenerating gas to burn combustible deposits therefrom, the catalyst being subsequently separated from the regenerating gas, and wherein a portion of the finer particles of said catalyst is continuously expelled from the system; the method of reducing the amount of inorganic impurities accumulated on said catalyst being circulated which comprises separating the regenerated catalyst into a coarser fraction and a finer fraction, initially contacting said residual oil containing said impurities with at least a portion of said finer fraction in an amount sufficient to absorb the higher boiling constituents of said residual oil containing said inorganic impurities, and thereafter contacting said oil with said coarser fraction of regenerated catalyst while at active cracking temperature and for a period sufficient to obtain the desired cracking thereof.

CHARLES W. TYSON.
